UNITED STATES PATENT OFFICE.

ANSON O. KITTREDGE, OF SLATE HILL, AND JOHN J. HOGAN, OF NEW YORK,
ASSIGNORS TO THE HOGAN ENGINEERING COMPANY, OF NEW YORK, N. Y.

RADIATOR-COUPING.

SPECIFICATION forming part of Letters Patent No. 450,160, dated April 14, 1891.

Application filed December 13, 1888. Serial No. 293,433. (No model.)

To all whom it may concern:

Be it known that we, ANSON O. KITTREDGE and JOHN J. HOGAN, citizens of the United States, residing, respectively, at Slate Hill, 5 Orange county, New York, and in the city, county, and State of New York, have invented certain new and useful Improvements in Radiator-Couplings, fully described and represented in the following specification and the 10 accompanying drawings, forming a part of the same.

This invention consists in a particular means for coupling the separate sections of radiators or cast-iron boilers together by means of an 15 internal sleeve, the construction of which is shown in the annexed drawings, in which—

Figure 1 is a side view of a radiator section or loop adapted for coupling by such sleeve, showing the face *n* adjacent to the seat *d*. 20 Fig. 2 is a section through two of such loops on line *x* *x* in Fig. 1. Fig. 3 is a side view of the sleeve; Fig. 4, an end view of the same with a coupling-collar applied thereto; and Figs. 5 and 6 are respectively side and end 25 views of the coupling-collar.

a are the circulation-tubes of a common form of radiator-loops, adapted to be coupled together in a series to form a heating-radiator.

b is a chamber at one end of the loop and 30 provided at its opposite sides, respectively, with the internal-threaded aperture *c*, and the aperture having a tapering seat *d* flared inwardly.

e is the coupling-sleeve having at one end 35 a thread *f*, fitted to the thread *c*, and *h* is a collar fitted internally to the sleeve and of conical form externally to fit the seat *d*. The sleeve is formed with a cylindrical seat *l*, having an annular V-shaped groove *g*, and the 40 interior of the collar is provided with a V-shaped rib *i*. An aperture with flattened sides *m* is formed through the sleeve to permit the circulation of steam or water through the same, the flattened sides serving to fit a wrench 45 for turning the sleeve within the chamber *b*.

The collar *h* may be divided at one side only, as shown in Fig. 4, or into two parts, as shown in Fig. 6, to permit its introduction into the chamber *b* through the aperture of the 50 seat *d*, the collar being made thin enough to

press together with its ends overlapped if divided at one side only.

The thread *f* is preferably projected above the cylindrical seat *l*, and the seat *d* is formed large enough for the insertion of the sleeve 55 within the chamber by passing such thread through the same.

In applying the coupling to unite two radiator-loops or boiler-sections the collar *h*, preferably divided at one side only, is compressed sufficiently to insert it within the chamber with the larger end of the cone adjacent to the thread *c*. The sleeve with its smooth end in advance is then inserted through the tapering seat *d*, and the seat *l* is 60 pressed within the collar, expanding it sufficiently to open the small rib *i* until the latter slips into the annular groove *g*. The face *n* adjacent to the thread *c* of another radiator-section is then applied to the face adjacent 65 to the tapering seat *d*, and the sleeve is screwed into the thread of such adjacent section by inserting a suitable wrench within the sleeve and turning it around. The screwing of the sleeve into the thread *c* draws the collar *h* 70 75 forcibly into the tapering seat *d*, and thus presses the faces *n* of the two sections or loops together. The pressure of the seat *d* upon the exterior of the collar jams the rib *i* closely into the groove *g*, by which the collar is held 80 firmly upon the sleeve, so as to practically become a part of the same in forming the coupling-joint. The joint between the radiator sections or loops is preferably made upon the opposed faces *n*, between which a packing *n'* 85 may be applied, if desired, and it is thus immaterial whether the sleeve and the coupling-collar form steam-tight joints with the thread *c* and the seat *d*, respectively.

By this construction of coupling the prepared sections are readily united together, and the coupling is also very cheap and effective, and the joint between them is easily made tight by a suitable packing between the 90 faces *n*.

In practice the conical ring *h* is made much lighter and thinner than is shown in the drawings, where it is represented larger than its proper proportions, in order to show its construction clearly. By making it light and 95 100

thin it is more cheaply constructed, is more readily applied to the end of the sleeve *e*, and is more readily pressed into close contact with the tapering seat *d* when applied.

5 It is obvious that the radiator-coupling described herein may be used in coupling together any castings having the chambers *b* therein and provided at their opposite sides, respectively, with the internal-threaded aperture *c* and the aperture having the tapering seat *d*. Such sections are shown in the boiler patented to John J. Hogan September 3, 1889, No. 410,162 and contain the same features (which render our coupling-sleeve applicable thereto) as the radiator-sections shown herein.

15 Having thus set forth the nature of our invention, what we claim herein is—

1. The combination, with the sections *a*, having the chambers *b*, provided, respectively, 20 at their opposite sides with a threaded aperture *c* and an aperture having tapering seat *d*, of the sleeve *e*, formed at one end with thread *f* and at the other end with a V-shaped groove *g*, and the collar *h*, having conical exterior and provided internally with the V-

shaped rib *i*, the whole arranged and operated substantially as herein set forth.

2. The combination, with the sections *a*, having the chambers *b*, provided, respectively, 30 at their opposite sides with a threaded aperture *c* and an aperture having tapering seat *d*, of the sleeve *e*, having an aperture through the same formed to fit a wrench and provided at one end with a cylindrical seat *l* and an annular V-shaped groove *g* and at the opposite 35 end with the thread *f*, projected above the seat *l* and fitted to the threaded aperture *c*, and the conical collar *h*, fitted to the seat *d* and provided with the V-shaped rib *i*, the whole arranged and operated substantially as herein 40 set forth.

In testimony whereof we have hereunto set our hands in the presence of two subscribing witnesses.

ANSON O. KITTREDGE.
JOHN J. HOGAN.
